CLAIM

The ornamental design for a lighted vehicle advertising system mount, as shown and described.

DESCRIPTION

FIG. 1 is a perspective view of a lighted vehicle advertising system mount, showing the new design;

FIG. 2 is an exploded view thereof;

FIG. 3 is a front view thereof;

FIG. 4 is a rear view thereof;

FIG. 5 is a top view thereof;

FIG. 6 is a left side view thereof;

FIG. 7 is a right side view thereof;

FIG. 8 is a bottom view thereof; and,

FIG. 9 is a front view of the design of FIG. 3 shown in a non-claimed environment.

The broken lines illustrate the environment of the design and form no part of the claim.
